UNITED STATES PATENT OFFICE.

FREDERICK W. BEAUCHAMP, OF INDIANAPOLIS, INDIANA.

DESIGN FOR A GLARE-GUARD FOR HEADLIGHTS.

50,090.

Specification for Design.

Patented Dec. 26, 1916.

Application filed September 18, 1916. Serial No. 120,899. Term of patent 14 years.

To all whom it may concern:

Be it known that I, FREDERICK W. BEAUCHAMP, a citizen of the United States, and a resident of Indianapolis, in the county of Marion and State of Indiana, have invented a new, original, and ornamental Design for Glare-Guards for Headlights, of which the following is a specification, reference being had to the accompanying drawing, forming part thereof.

Figure 1 is a perspective view of the glare

guard. Fig. 2 is a front elevation of the glare guards, mounted on a nonessential form of automobile headlights, showing my new design, the shading of the jewels at the points of the guards being intended to indicate green and red for right and left guards.

I claim:

The ornamental design for a glare guard for headlights, as shown.

FREDERICK W. BEAUCHAMP.
